UNITED STATES PATENT OFFICE.

WARREN H. WILDRICK, OF PHILLIPSBURG, NEW JERSEY.

SHADE AND CURTAIN HANGER.

1,175,030.

Specification of Letters Patent. Patented Mar. 14, 1916.

Application filed March 8, 1915. Serial No. 12,938.

To all whom it may concern:

Be it known that I, WARREN H. WILDRICK, a citizen of the United States, residing at Phillipsburg, in the county of Warren and 5 State of New Jersey, have invented certain new and useful Improvements in Shade and Curtain Hangers: and I do declare the following to be a full, clear, and exact description of the invention, such as will enable 10 others skilled in the art to which it appertains to make and use the same.

This invention relates to curtains and shades, and more especially to hangers therefor; and one object of the same is to produce 15 a curtain-pole fixture which may be applied to the shade fixture at any time without removing the latter or altering the construction of either.

Another object is to produce an improved 20 form of base member and improved means for connecting the shade fixture therewith so that if it be desirable to adjust said shade fixture vertically or laterally at the time the curtain fixture is applied, or at any other 25 time, it can be done.

These objects are accomplished by making 30 the parts of this hanger in a peculiar manner as fully set forth in the following specification and claims, and as shown in the drawings wherein—

Figure 1 is a perspective view of one corner of a window, with this improved hanger attached to its frame. Fig. 2 is a side elevation of the hanger with all its members 35 complete, and Fig. 3 a plan view thereof. Fig. 4 is a perspective detail of the base member, Fig. 5 a similar view of the shade-roller bracket, and Fig. 6 a similar view of the curtain-pole bracket.

40 Referring more particularly to the drawings, the numeral 1 designates the base or support for this hanger, of which it will be understood there are two, one right and one left for each window. This base comprises 45 a horizontal arm 2 and a vertical arm 3, the former being longitudinally slotted as at 4 whereby it may receive attaching screws 5 which pass into the top of a window frame and which I would not set at the extremities 50 of the slot but prefer to dispose slightly remote therefrom, so that the base member may be adjusted longitudinally at any time. The upright member is provided with a threaded hole 6 about where shown, and at 55 its lower end with a forwardly projecting tongue 7. The whole is stamped from one

sheet of metal, and suitably ornamented to present a neat appearance.

The shade fixture is also made in right and left as will be understood, and likewise 60 stamped from one piece of sheet metal suitably ornamented. It comprises a horizontal arm 12 bent at right angles as at 11 and turned forward as at 10, and a vertical arm 13 having a longitudinal slot 14 slidably 65 mounted over said tongue 7 and adapted to receive a screw 16 which enters said hole 6 in the base member, by means of which this fixture can be vertically adjusted at any time. The forwardly projecting portion 10 70 of the horizontal arm has a deep notch 15 formed in its upper edge for the trunnion of the shade roller, and is notched in its lower edge adjacent the angle 11 as seen at 17, while the upper edge of the horizontal 75 arm 12 is similarly notched adjacent the said angle as seen at 18. The outer end of the arm 10 is turned aside and formed into an upwardly opening hook 19.

The curtain-pole fixture is by preference 80 formed of a single piece of stout but spring wire, also suitably ornamented to present a neat appearance and to match the ornamentation of the other members of this hanger. Near its outer end I give it a U-shaped bend 85 20 for the reception of the curtain pole (not shown), and one arm of this bend is continued into what might be called the body of the fixture and extends outward from the U-shaped bend and slightly downward as 90 seen at 21, and at the inner end of the body it is turned sharply upward at an angle 22 95 into an upstanding arm 23 which is a little out of the plane of the body as will be seen, the upper extremity of the arm 23 being 95 hooked as shown at 24. In applying this fixture to the shade fixture, the wire device is grasped by its U-bend 20 and its upstanding arm 23 is passed under the arm 10 of the shade fixture until the hook 24 can be 100 engaged with the notch 18. At this time the bend or angle 22 will engage the notch 17 and the body comes opposite the hook 19 whose upper end is by preference slightly beveled as shown at 29: and up this bevel 105 the body is pushed until it snaps into the hook 19 by its own resiliency. Thereafter the weight of the curtain-pole in the U-bend 20 will tend to bear the arm 21 downward and depress it more firmly into engagement with the hook, while the tendency 110 is resisted by the firm engagement of the

inner end of this member with the notches in the shade fixture.

With a hanger as above described, it is proposed to apply the base members to the window frame and leave them there, and ordinarily the shade fixtures are attached to the base members and also left in place whether the shades are removed or not. The slots in the horizontal arm of the base and the vertical arm of the fixture obviously permit adjustment of parts so that the hanger may be fitted to a shade roller of any length, and the roller may be set exactly horizontal. Its trunnions are now inserted in the openings 15, and its use is that ordinarily given to spring-roller shades.

In the fall when it is desired to put up a curtain pole and curtains or lambrequins, the wire curtain fixtures are snapped into place as above described, and the curtain poles laid in the U-bends in a manner which will be clear.

Attention is directed to the fact that when the parts are in their working positions the body 21 of the curtain fixture passes across the arm 10 of the shade fixture at such a point that it is beneath the opening 15 in the latter which receives the trunnion of the shade. The result of this detail of construction is that the shade may be lifted out of place at any time it needs repair or cleaning, with as much ease as the curtain pole and its curtain may be lifted out of the U-bends 20 when it needs repair or cleaning.

What is claimed as new is:

1. The combination with a shade bracket having a notch in its upper edge adjacent

Copies of this patent may be obtained for five cents each, by addressing the "Commissioner of Patents, Washington, D. C."

one extremity, an outstanding arm connected with the bracket at said extremity and having a notch in its lower edge, a laterally extending hook at the free end of said arm; of a curtain fixture of spring wire whose body is adapted to lie in the hook and extend the length of said arm on one side thereof, the inner end of said body being bent laterally and extended under the lower edge of said arm in the notch therein, the free inner end being then bent laterally upward on the opposite side of the arm, the free end of said upstanding portion being provided with a hook adapted to engage the first mentioned notch.

2. In a hanger of the class described, the combination with a base comprising a right-angled member whose horizontal arm is slotted and whose upright arm is pierced with a threaded hole and provided with a forwardly projecting tongue at its lower end; of a shade fixture comprising horizontal and upright arms the latter of which is provided with a vertical slot adapted to slidably engage said tongue and to receive a screw which engages said threaded hole in the base, and means carried by the horizontal arm for supporting the trunnion of a shade roller.

In testimony whereof I have hereunto set my hand in presence of two subscribing witnesses.

WARREN H. WILDRICK.
